[57] CLAIM

The ornamental design for insulating sleeve for a terminal, as shown and described.

DESCRIPTION

FIG. 1 is a perspective front view of an insulating sleeve for a terminal embodying the present design;

FIG. 2 is a front view thereof, a rear view being a mirror image of a front view;

FIG. 3 is a top plan view thereof;

FIG. 4 is a right side view thereof;

FIG. 5 is a left side view thereof;

FIG. 6 is a bottom view thereof; and,

FIG. 7 is a typical referential perspective view thereof.

The broken line showing of the conductor and terminal in FIG. 7 is included for the purpose of illustrating the environment of the insulating sleeve only and forms no part of the claimed design.
